UNITED STATES PATENT OFFICE.

JOHN O. NEIKIRK, OF CHICAGO, ILLINOIS, ASSIGNEE TO NATIONAL DUMP CAR CO., OF CHICAGO, ILLINOIS, A CORPORATION OF MAINE.

RAILWAY CAR.

Application filed November 12, 1919. Serial No. 337,415.

To all whom it may concern:

Be it known that I, JOHN O. NEIKIRK, a citizen of the United States, residing at Chicago, in the county of Cook and State 5 of Illinois, have invented certain new and useful Improvements in Railway Cars, of which the following is a specification.

This invention relates to railway cars, and more particularly to door constructions 10 and arrangements in connection therewith.

It is common experience among car operators to have difficulty in closing floor or dump doors which at times are prevented from being entirely closed by pieces of coal 15 or other material becoming lodged between the door edges and associated frame members of cars.

Therefore, one object of my invention is to overcome this objectionable feature by 20 providing such floor or dump doors with means for cutting through such clogging material so that the doors may be completely closed with the minimum amount of effort.

Another object is to provide a door having 25 parts adapted to reinforce associated frame members.

Another object is to provide a novel door construction for general service cars adapted to meet the various requirements under serv- 30 ice conditions.

These and other objects are accomplished by means of the arrangement disclosed on the accompanying sheet of drawings, in which—

35 Figure 1 is a transverse sectional view of a general service car embodying my invention;

Figure 2 is a sectional view of my im- 40 proved door construction taken in the plane of line 2—2 of Figure 1;

Figure 3 is a plan view of a modified form of door embodying my invention; and

Figure 4 and Figure 5 are sectional views taken respectively along the line 4—4 and 45 line 5—5 of Figure 3.

The various novel features of my invention will be apparent from the following description and the drawings, and will be particularly pointed out in the appended claims.

50 Referring to the figures of the drawings, it will be noted that I have disclosed my invention in connection with a general service car having sides 10, ends 11 and a floor composed largely of my improved doors 12, 55 which preferably are pivotally mounted at

13 to the center sill structure. The car includes cross frame members 15 and supporting stop members 16, which limit the opening movement of the dump doors 12. My improved door may be of a composite 60 nature, being made of wood and metal, as shown in Figures 1 and 2, or it may be entirely of metal, such as pressed steel, as shown in Figures 3 to 5 inclusive.

Reference being had particularly to Figure 2, it will be noted that I have shown the cross frame members 15 as having the usual flanges 17, while overlie the edges of the door 12. As mentioned hereinabove, great difficulty sometimes is encountered in 65 attempting to close these doors when coal or other material is wedged in between the flanges 17 of the frame members and the edges of the doors. To overcome this objectionable feature, I have provided a door 70 structure in which the edges of the door take the form of metal angle members 18, the upper edges 19 which engage the flanges 17 being knife edges, so that any coal or other material which is clogged in between 75 the edges 19 and the flanges 17 will be readily cut by the cutting edges 19 which are unassociated with any grooves wherein material could collect, whereupon the door may be moved into closed position with relatively 80 little effort. The angle members 18 of the door are connected by suitable wood members 20, the outer one of which is inclined as at 21 for engaging the under surface of a longitudinally extending side member 22. 85

The doors 12 are supported in closed position preferably by a laterally movable shaft 23, which is movable in a slot 24 formed in the cross frame members 15. As shown at the left hand side of Figure 1, 90 the doors 12 are supported in their upper or closed position, the shaft 23 being located under the door. The doors may be released by an outward lateral movement of the shaft 23. When the door is held in its 95 closed position by the shaft 23, the vertical flanges 19 of the door angle members 18 engage the horizontal flanges 17 of the cross members 15 and act in a manner to reinforce the latter.

Referring particularly to Figures 3, 4 and 5, I have shown a floor dump door made entirely of pressed steel, the vertical side flanges 25 of which are provided with cutting edges 26 for cutting through clogging 100 110

material which may be caught between such edges 26 and the horizontal flanges 17 of the cross frame members 15. These vertical flanges 25 also engage the horizontal flanges 17 of the cross members 15 for reinforcing the latter as mentioned in connection with doors shown in Figures 1 and 2. This pressed steel door is provided with corrugations 27 which extend crosswise of the car and in the line of flow of material as it is being dumped from the car, thereby in no wise acting as an obstruction, but at the same time greatly strengthening the door. By thus corrugating the door, the usual door battens are eliminated.

It will be noted that the side flanges 25 of the door extend vertically upwardly from the body of the door and that the other edges 31 of the door extend vertically downward from the body of the door, thereby giving great strength to the latter. The outer and inner edges of the doors are provided with flat portions 28 and 29 respectively for co-operating with stationary portions of the car in a manner similar to that shown in Figure 1 of the drawings.

At the inner ends of the door, demountable hinge members 30 are provided, the hinge member 30 in each case being mounted 30 within the channel portion of the corrugation, where it is out of the way and does not form an irregular surface on a used portion of the door. The type of hinge here used forms the subject matter of Hart application, Serial Number 332,638, filed October 23, 1919, and accordingly will not be claimed herein; but it may be stated that the hook portion of the hinge simply hooks over its supporting pivot in a manner such that the 40 door is readily demountable without the use of any tools whatsoever.

These doors are simple, strong and relatively light in construction and are adapted to meet the requirements of successful 45 commercial operation.

It is my intention to cover all modifications of the invention falling within the spirit and scope of the following claims.

I claim:

50 1. A railway car having a dump door having straight vertical flanges with cutting edges for cutting through material lodged between such edges and an associated frame part whereby the door may be completely closed.

60 2. A railway car having a stationary frame member, and a door having a vertical flange with a cutting edge for cutting through material lodged between such edge and frame member and being unassociated with a materials collecting groove whereby the door may be completely closed.

65 3. A railway car having a stationary frame member with a horizontal flange, and a door having a vertical flange with a cutting

edge engageable with said frame member when in closed position for cutting through material lodged between such cutting edge and horizontal flange of the frame member and being independent of any associated materials collecting groove whereby the door may be completely closed.

70 4. A railway car having a stationary frame member with a horizontal flange, and a door having a vertical flange underlying 75 and directly engaging said horizontal flange for supporting the latter when the door is in closed position, said vertical flange having a cutting edge for cutting through any material lodged between said edge and horizontal flange whereby the door may be completely closed.

75 5. A railway car having a dump door formed of pressed material having straight vertically arranged flanges with cutting 85 edges extending above the adjacent body of the door for cutting through material lodged between said edges and associated frame parts whereby the door may be completely closed.

90 6. A railway car having a dump door formed of pressed material having vertically arranged flanges with cutting edges extending above the adjacent body of the door for cutting through material lodged 95 between said edges and associated frame parts whereby the door may be completely closed, said door having formed therein corrugations for strengthening the said door.

7. A railway car having a dump door 100 formed of pressed material having vertically arranged flanges with cutting edges for cutting through material lodged between said edges and associated frame parts whereby the door may be completely closed, said door 105 having strengthening corrugations formed in the line of flow of material as it is being dumped.

8. A railway car having a dump door with vertical material cutting flanges at its 110 edges and with corrugations intermediate the edges extending in the line of flow of dumpable material as it is being dumped.

9. A railway car having a dump door with vertical flanges at its edges and with 115 corrugations intermediate the edges extending in the line of flow of dumpable material as it is being dumped, and hinge members mounted in the channel portions of said corrugations.

120 10. A railway car having a dump door of pressed metal in which the side edges are in the form of upwardly extending vertical cutting flanges and in which the other edges are downwardly extending vertical flanges 125 with respect to the body of the door for strengthening purposes.

11. A railway car having a dump door of pressed metal in which the side edges are in the form of upwardly extending vertical 130

cutting flanges and in which the other edges are downwardly extending vertical flanges with respect to the body of the door, said door being provided with corrugations for 5 strengthening purposes.

12. A railway car having a dump door of pressed metal in which the side edges are in the form of upwardly extending vertical cutting flanges and in which the other edges

are downwardly extending vertical flanges 10 with respect to the body of the door, said door being provided with corrugations for strengthening purposes, and hinge members mounted in said corrugations.

Signed at Chicago, Illinois, this 5th day 15 of November, 1919.

JOHN O. NEIKIRK.
